UNITED STATES PATENT OFFICE.

BENJAMIN S. SEAMAN, OF CANTON, OHIO.

DESIGN FOR A SUPPORT FOR SADDLE-SEATS.

SPECIFICATION forming part of Design No. 26,384, dated December 8, 1896.

Application filed October 12, 1896. Serial No. 608,666. Term of patent 7 years.

To all whom it may concern:

Be it known that I, BENJAMIN S. SEAMAN, a citizen of the United States, and a resident of Canton, county of Stark, State of Ohio, 5 have invented and produced a new and useful Design for Bicycle-Seat Supports, of which the following is a full, clear, and exact description, reference being had to the accompanying drawings, making part of this specification.

My invention relates to a new design for bicycle-saddle-seat supports.

Figure 1 of the accompanying drawings is a view in perspective of the invention. Fig. 15 2 is a cross-section on line *x x*, Fig. 1; and Fig. 3 is a similar view on line *a b*, Fig. 1.

The seat-support is formed as shown in Fig.

1, that is, it is folded over upon itself and divided into strips A, spread out in fan form and secured to the cantle B. The front end 20 C is secured to the pommel-frame D.

The leading feature of the design consists of the solid front portion C, the strips integral therewith and spread apart in fan form and secured to the cantle-frame. 25

What I claim is—

The design for a bicycle-saddle-seat support, substantially as shown and described.

In testimony whereof I have hereunto set my hand this 9th day of October, A. D. 1896. 30
BENJAMIN S. SEAMAN.
